LIQUID FUEL BURNER

Brooks Walker, Piedmont, Calif.

Application January 16, 1942, Serial No. 426,993

6 Claims. (Cl. 158—81)

1

This invention pertains to small, collapsible camp stoves for use by campers, cross-country skiers, mobile troops, and others requiring heat for cooking, as well as possibly heating a small tent. Heretofore such stoves, as used by explorers, have been made in foreign countries and have a large number of loose parts which must be packed in a separate can or container, involving the possibility of losing some of the parts, thus rendering the stove useless. A further object of this invention is to provide a stove of minimum size that can be folded into a small space with the legs forming a substantial protection to the various parts when in the folded position. A further object of this invention is to provide means whereby a single valve fed by a wick from the fuel tank, passing through the air body above the fuel, will admit a combination of fuel and air during the starting operation prior to heating the generator to a point where the fuel is vaporized, as this is necessary in temperatures around thirty below zero where gasoline will not readily light in an open pan such as a priming cup, and alcohol is normally required with the complication of having to provide two kinds of fuel. A further object of this invention is to provide a starting tube whereby an auxiliary tube when placed in the starting position intercepts the fuel-air spray and blows it directly on the generator where, during the starting operation, a hot flame impinges directly on the generator, heating the generator to operating temperature in twenty seconds to a minute, depending upon conditions, thus speeding the operation materially over starting without such a tube and waiting for heat to be transmitted through the burner cup to the generator. Another object of the invention is to provide a construction whereby a vertical jet over a fuel tank can be controlled by a vertical valve with a cleaning wire going through the jet. Another object of the invention is to provide a construction whereby a short cylindrical tank can be used with a burner intake coming out of the side of the tank, fed with a wick, so that the stove may be turned with the burner up for starting where the wick will pass through the air above the fuel during the starting operation, and when laid down on its side in the running position, the wick will be completely submerged most of the time, thus conserving air pressure. A further object is to provide a stove in which maximum fuel capacity is available, while still allowing the stove to be nested within an ordinary mess cooking pot such as troops carry, usually six

2

to seven inches in diameter and four to five inches high.

The invention is illustrated by way of example in the accompanying drawings, in which:

3 Figure 1 is a side elevation, partly cut away, showing one form of the invention.

Figure 2 is a side elevation, sectional view through an alternate type of valve construction which might be used in connection with Figure 1.

10 Figure 3 is a top, plan elevation of the stove illustrated in Figure 1.

Figure 4 is a side elevation of an alternate type of stove construction.

15 Figure 5 is a perspective view, partly cut away, of the stove, embodying another form of the invention.

Figure 6 is a plan view of the stove shown in Figure 5, collapsed into its carrying position and nested within a cooking pot.

20 Figure 7 is a plan view of still another type of stove embodying the invention.

Figure 8 is a side elevation view, partly cut away, of the stove as shown in Figure 7.

25 Figure 9 is a transverse sectional view of the modification shown in Figure 5, with the stove in starting position.

In all figures, like numerals of reference refer to corresponding parts in the various figures.

In Figures 1, 2, and 3 I have shown a fuel tank 30 carrying a supply of fuel 11 and provided with a filter cap 12 preferably of the conventional type such as Coleman uses on their gas lamp with an air vent which can relieve the pressure without danger of blowing up the tank. A pump 13 is provided with a pump handle 13a of the conventional type with an outlet 13b preferably above the fuel level so that any leakage through the pump will not leak fuel into the pump. This pump is of the conventional type with a cup leather plunger, check valve, and preferably a screw-threaded shut-off valve in addition, similar to that used in the Coleman type gasoline lamps. A bushing 19 is secured by brazing, silver soldering, swaging, or other suitable means to the tank and the valve 20 is threaded into the bushing 19. Within the upper end of the valve 20 is threaded the burner jet element 29 and is adapted to receive valve 20. The valve 20 is supplied with fuel through wick 21 held in place by wire 22 which also helps insert the wick when the valve is inserted into place.

Between the wick 21 and the control valve 23 is preferably inserted a rolled metal screen 24 which prevents parts of the wick from getting into the valve seat and preventing tight closing.

A jet cleaner wire 25 is suitably held in a holder 26 adjustably secured to cleaner block 28 by being swedged into same or by screw threads and lock-nut 27. A cleaner cam actuator 30 of the type used on Coleman gas lamps is provided with a conventional type of stuffing box. Control valve 23 is operated by valve handle 23a and it has a conventional stuffing box secured by nut 23b.

A burner cup 35 of the Primus type is provided with spider 36 on which the fuel spray impinges for a suitable spreading and burning in the burner cup 35. The burner cup is secured to a sleeve 37 which is secured by threads to the outside of the valve housing 20. On the lower end of sleeve 37 is provided a shoulder and nut for securing bracket 38 for supporting a starting tube 39 which is pivoted to the bracket at 40. This starting tube can assume the dotted line position shown in Figure 1 for starting, when the fuel will be deflected through the tube and burn against the threaded portion of the valve housing around the cleaner wire control to heat it to a temperature at which the gasoline will be vaporized, at which time the operator can flip the tube 39 into the position shown in full lines in Figure 1 where its top edge will strike the edge of the hole through the burner cup to keep it from coming clear out.

The three legs 50 are suitably secured to the fuel tank by bearings 51 which allow the legs to swivel. On the lower edge of the legs 50 are circles 50a covered by thin metal 50b to give footing in mud or snow and to make the stove stable when supporting a heavy load of material being cooked. The upper ends of the legs 50 are looped and support two tie-wires 52 on each leg. The ends of the tie-wires are looped through the loops in the legs 50 so that they cannot be lost. The other ends of the tie-wires hook into holes through the lip of the burner cup 35 and make the structure relatively rigid, particularly if the burner cup is screwed fairly tightly on the upper end of the valve housing 20. When it is desired to carry the stove, the tie-wires 52 are all disconnected from the burner cup 35 and folded down next to the legs 50. The legs 50 are then swung around so that the feet 50a and 50b nest under the center of the fuel tank, each touching the other about the center. This leaves the upper end of the legs 50 nested against the burner cup to protect same and allows the packing of the stove in a minimum of space.

In Figure 2 I have shown an alternate form of valve construction in which a valve housing 60 is provided with a screw-threaded valve stem 61 suitably packed by conventional packing gland 62, and operated by a non-heat-transmitting handle 61a. The cleaning wire 66 in this instance is secured in a holder 65, the lower end of which is provided with a shoulder 67 which is yieldably urged into a wire-retracted position by spring 68. The lower end 69 of the wire holder is so arranged as to butt against the taper end of the valve stem 61 so that when the valve stem is screwed into a wide open position, the cleaning wire is retracted out of the fuel orifice 70 to a position directly below the orifice where there is a taper hole for guiding the wire back into the orifice. When the fuel valve 61 is in its closed position, the cleaning wire is forced into its cleaning position, passing through the fuel orifice.

Where it is desirable to use a heat-resistant, non-corrosive type of metal such as stainless steel or Nicrome for the generator 72, it may be suitably secured to the valve housing 60 by a gland

nut 73 and is preferably provided with threads on the outside for the mounting of the burner cup which may be screwed down to a position against the gland nut 73 for packing in a minimum of space, and screwed up against auxiliary jam nut 75 when ready to operate as a stove.

In Figure 4 I have shown an alternate type of construction wherein a slightly different shaped tank 80 is used with the usual filter cap 12, air pump 13, and legs 50, similar to those shown in connection with Figures 1 and 3. However, here I have shown a vertical type valve, preferably with a cleaner wire located on the end of the valve stem and projecting through the orifice. The wick 21 extends through the vertical tube 81, through the elbow, and through the horizontal extension 82a of the valve housing 82. A cup 83 is preferably secured to the gland nut on the stuffing box and the valve handle 93 which is located directly above the fuel tank. This cup 83 catches any fuel which may drip from the starting tube 39 during the starting operation, and keeps the fuel off of the valve handle and the fuel valve. It also protects the valve handle 93 from radiated heat.

Figure 5 shows an alternate construction in which a cylindrical tank 90 is provided with an air pump 13 at one end and a filter cap at the other end, and with a fuel valve housing 92 secured to the side of the tank and fed by a wick 21. The burner cup 35 is preferably provided with a starting tube 39 and a valve handle 93 which is above the level of the supporting surface. Tubes 94 and 95 are suitably attached to either end of the fuel tank, though these could be replaced by clips formed from or attached to the end of the fuel tank rather than tubes. A short bracket rod 96 extends upwardly through said tube 94, forming a loop at the top, through which is pivoted rod 97, then out horizontally with a depression to receive rod 98, down vertically and back horizontally to a loop around the lower end of the vertical portion of the rod 96. The rod 98 and the corresponding rod or brace wire 99 complete the supporting structure, the other end of rod 98 being connected to the rod 97, which has its free end inserted in the upper end of tube 95, and the other end of brace wire 99 being inserted in the lower end of tube 95 to form a rigid structure suitable for holding heavy cooking pots. The lower run of the rod 96 carries a foot 96', which supports the stove on snow or soft ground. A guard 100, preferably secured to the jam nut 92a on the valve housing, protects the tank against excessive heat transmission, particularly by radiation and preferably has a depression 101 formed therein to catch fuel which may drip during the starting operation.

Brackets 103 are attached to the bottom of the fuel tank 90 to form supports therefor and to prevent the heat from the fuel tank from melting the snow. Also, supports 103 together with the tank form a support for starting, as shown in Figure 9, in which the fuel valve 92 is substantially vertical, which allows the wick 21 to pass through the air chamber to pick up air during the starting operation to give the necessary atomization for instant starting in cold weather.

Figure 6 shows the same stove in its folded position.

In Figures 7 and 8 I have shown an alternate construction in which a substantially round fuel tank 120 is provided with air pump 121, a filter plug 122, burner cup 35, a fuel valve control 61a, a starting tube 39, and a fuel valve body and

valve construction 60 similar to that shown in Figure 2. A wire pot-holder 125 is suitably pivoted or secured to the tank at 126 and 127 so that it can assume a position about the perimeter of the tank when stored, or vertically when carrying, or as shown when cooking, and may be suitably supported by rods 130 and 131 which may either go to the supporting surface or back to the rim of the fuel tank. To collapse the pot-holder, the rods 130 and 131 are disengaged from the tank and the ring-forming member is swung around its connection to over-lie the tank. A guard plate 133 is preferably inserted between the burner cup 35 and the fuel tank to protect the same from getting too hot. A wick 21 feeds fuel to this valve housing 60 and the stove is preferably started by placing it with the valve up so that the wick passes through the air-pressure chamber to pick up air for starting and then when the stove is set down in the operating position, the valve takes fuel only and no air after the generator is up to temperature.

While I have discussed this invention primarily in connection with a folding camp or troop stove, I wish it to be understood that the construction of a valve fed by a wick passing through the pressure air chamber above the fuel to pick up air and fuel during the starting operation, as well as the starting tube for picking up the fuel-air spray from the nozzle and piping it around to impinge on the generator for quick starting, as well as the valve construction, cleaning wire construction, and the other details disclosed herein are equally applicable to gasoline or fuel-oil lamps of the so-called Coleman type, as well as gasoline or fuel-oil blowtorches and any other device where instantaneous starting on a fuel-oil flame is desirable.

I also wish to point out that I do not wish to limit myself to the exact details or modes of operation set forth in this application and drawings, for it will be obvious that wide departure may be made in the way of details without departing from the spirit and scope of my invention, which is as set forth in the following claims.

I claim as my invention:

1. A burner operated on vaporized liquid fuel having a burner cup, a generator, a fuel jet, and a starting element forming a hollow passage from a point adjacent the jet to a point adjacent the generator so a flame may be directed against said generator during the starting operation, said starting element being adapted to be moved out of engagement with the fuel from said fuel jet, and said generator being directly below and forming a straight passage to said fuel jet.

2. A burner operated on vaporized liquid fuel having a burner cup, a generator, a fuel jet, and a starting tube forming a hollow passage from a point adjacent the jet to a point adjacent the generator so a flame may be directed against said generator during the starting operation, said starting tube being adapted to be moved out of engagement with the fuel from said fuel jet, and said generator being directly below and forming a straight passage to said fuel jet.

3. A burner for vaporized fuel, having a generator, a wick for supplying said generator with a liquid fuel, a tank for said fuel, and manual means for supplying said tank with air pressure above atmospheric pressure from outside said tank, said burner having a starting position in which the wick passes through the air containing portion of the tank and a position for sustained operation with the wick completely immersed in said liquid fuel.

4. A burner for operating on liquid fuel having a wick, a fuel tank, manual means for adding outside air pressure above atmospheric pressure to said tank, and a valve between said wick and said burner, said tank having means adapted to support it in either of two positions, one for starting where said wick will provide passage to said burner for liquid fuel under pressure mixed with air from inside said tank, and an operating position where said wick provides said burner with liquid fuel but no air from inside said tank.

5. A vapor fuel burner comprising a tank having a straight vertically positioned generator mounted thereon, the upper end of said generator terminating in a fuel jet and a surrounding burner cup, and a tubular, curved starting element swingingly mounted to project into the cup and divert the fuel mixture from the jet to a point adjacent the generator to heat the generator during starting.

6. A vapor fuel burner comprising a tank having mounted thereon a generator, a fuel jet and a burner cup in vertical alignment and immediately adjacent one another, forming a straight short passage for generating and burning the vapor, and a tubular, curved starting element swingingly mounted on the generator and normally having its upper end adjacent the wall of the cup, said element being adapted to project into the cup and divert the fuel mixture from the jet to a point adjacent the generator to heat the generator during starting.

BROOKS WALKER.
